ABSTRACT

A method and apparatus for producing a color corrected and rastered reproduction wherein a continuous tone picture is photoelectrically scanned and combined with the output of a second scanning head which scans a raster pattern to be superimposed over the picture and the outputs of the two heads are combined and applied to a recording head through a threshold circuit.

A cathode ray tube is provided for allowing the method to be monitored so as to assure that the proper reproduction is occurring.

APPARATUS FOR PRODUCING CORRECTED
PHOTOGRAPHIC COLOR RASTERED REPRODUCTIONS
BACKGROUND OF THE INVENTION

1. Field of the Invention

The present invention relates in general to a method and apparatus for recording rastered pictures of originals by photoelectrically scanning continuous tone pictures and preferably for producing rastered corrected photographic color separations by means of electronic color scanners.

2. Description of the Prior Art

In the prior art half-tone pictures are always rastered in relief and offset printing. Consequently, the corrected color separations produced for the purpose of reproducing colored half-tone pictures must be rastered. The color separation printing plates are chemographically etched and formed from the colored half-tone pictures.

One prior known method provides rastering of photographic color separations after recording while it is being photographically copied together with a contact raster foil. The raster fields of a contact raster are vignetted in known manner, in other words, the density of the blackness decreases continuously from a maximum value in the middle of the field to the edge. A film of very high contrast and with a pronounced threshold of sensitivity is used as the copying material.

Because of the vignetting of the contact raster and the threshold sensitivity of the film, a condition is reached where the size of each raster dot is determined by the local brightness value of the continuous tone picture.

In place of a vignetted contact raster, a sharply defined glass raster may sometimes be used which is placed at a certain distance in front of the continuous tone picture so that its raster elements are formed with the same degree of fuzziness as the vignetting.

The known method for later rastering has, however, a drawback due to the unfavorable and unavoidable property of the film material. As is known, the steepness of the film gradation and the position of the threshold of the sensitivity which define the sizes of the raster dots are influenced by the developing time, the temperature and the condition of the developing liquid in the developing tank as well as by the agitation of the film in the developing tank.

The uncertainty of the size of the rastered dots thus caused has an especially disturbing effect, when it is to be used to produce color separations which will then be combined to form multi-colored prints.

SUMMARY OF THE INVENTION

The invention provides a method and apparatus in which picture signals are obtained by photoelectrically scanning the un rastered continuous tone picture and then recording it in raster fashion according to the invention with a superimposed raster having a vignetted raster field or a raster effectively equivalent which is superimposed over the original picture. The electrical scanning pulses obtained from said such superimposition are fed to a recording head which is controlled thereby through a threshold value circuit.

When the imprecise threshold of the sensitivity of the film material is reached, the method according to the invention allows a threshold to be retained by electrical circuit means which can be maintained sufficiently constant without much difficulty. The threshold value is determined by the level of a d.c. voltage opposed to the voltage of the scanning pulse and this threshold voltage is such that the brightness value associated therewith is higher than the highest threshold of sensitivity to be expected of the recording media used for recording.

The superposition of the raster in the simplest case as, for example, in a black and white continuous tone picture original, may consist in applying the raster foil onto the picture original to be scanned.

However, if it is desired to produce color separations from a colored picture original, then each color separation should have a different raster angle to avoid the formation of a moiré structure. In this case the rastering is preferably done by photoelectrically scanning the raster foil by means of a separate scanning head and the scanning pulses which are thereby obtained or superimposed on the picture pulses.

If a sharply defined raster is to be used in place of a vignetted raster, the raster elements are focused on the scanning head with the same degree of fuzziness as the vignetting.

There is already known a method for direct rastered recording in which the raster dots are produced by lightflashes whose intensity is controlled by the brightness via the scanned picture original. This method is very expensive and results in expensive equipment and also leads to difficulties because of the requirement for altering the raster angles. With the present invention, on the other hand, an alteration of the raster angle can be accomplished by simply moving the raster foil.

As is known, the gradation curve of a very hard film material has a certain edge obliquity, whereby the recorded raster dots become unclear. In some cases, this may be desired, particularly if partial corrections of the printed type can be made by subsequent etching of the raster elements. If, on the other hand, sharply defined raster dots are desired, this may be achieved by the present invention, by utilizing an overdriven amplifier which is fed with electric scanning pulses. The overdriven amplifier changes the shape of the scanning pulses, which due to the vignetting of the raster fields, consists in a wavy voltage which has oblique flanks, into a voltage of square waveform whose steep edges cause sharp definition of the drawing.

To test the raster dots before the final recording or to be able to correlate the gradation range of the picture original initially to the corresponding range of the variation of the size of the raster dots, an auxiliary device may be used. This consists in a cathode ray tube having a target whose horizontal beam deflection is controlled in response to the picture scanning movement and whose vertical beam deflection is controlled by the picture scanning advance and whose dot brightness is controlled in dependence upon the amplitude of the electric pulses appearing at the output of the threshold value circuit. The screen of the cathode ray tube produces a picture which may be continuously monitored.

Other and further objects, features and advantages of the present invention will become apparent to those skilled in the art from the following detailed disclosure thereof and the drawings attached hereto and made a part hereof.

BRIEF DESCRIPTION OF THE DRAWINGS

FIG. 1 is a schematic view of an embodiment for carrying out the method of the invention; and

FIG. 2 illustrates a raster picture shown on the screen of a cathode ray tube for monitoring the system.

DESCRIPTION OF THE PREFERRED EMBODIMENT

FIG. 1 illustrates an original picture 2 that might be, for example, a multi-colored picture which is attached to the surface of a drum 1 mounted on a suitable drive shaft 27. The picture 1 is scanned by a photographic scanning head 3 which is mounted on a mechanical movement 30 that moves it longitudinally of the drum as the drum is rotated.

A drum 4 is also mounted on the shaft 27 and a recording medium 5 is mounted on the surface of the drum and a recording head 6 which includes a light source 7 is moved by the mechanical movement 30 relative to the drum 4 to record on the medium 5 the color separation of the original. A motor 28 drives the shaft 27.

A screen 10, which carries the raster pattern to be superposed over the picture content, is attached to the surface of a third drum 9 also mounted on the shaft 27 and which is scanned photographically by means of a scanning head 11

which is also driven by the mechanical movement 30. The mixing or superimposing stage 12 receives inputs from the scanning head 11 and the scanning head 3. A color computer 8 is mounted between the scanning head 3 and the mixing stage 12 to provide for desired color emphasis.

The raster pulses from the scanning head 11 and the output of the scanning head 3 are combined in the mixing stage 12 and the output pulses of the mixing stage are fed to a threshold stage 13 and to an amplifier 14 which supplies an input to the recording head 6.

A cathode ray tube is used as a monitoring device to check the raster structure produced. The tube 15 has a target screen 26 as best shown in FIG. 2 which retains the recording produced by the cathode ray beam as an electrostatic charge image. Such a charge picture is retained for a longer time than if it were recorded on a persistence screen.

The cathode ray tube 15 has vertical deflecting plates 16 which are driven by a voltage supplied by a variable potentiometer 17. The wiper contact 25 of the potentiometer 17 is connected to the mechanical movement 30 which drives the scanning heads 3, 11 and 6 so that the vertical deflection beam is controlled as a function of the advance of the picture scanning.

Horizontal deflection plates 18 are connected to the output of a time base generator 19 which is triggered by an output of the scanning head 11. A single trigger pulse results in a single horizontal deflection of the cathode ray beam and subsequent beam fly-back. The trigger pulse occurs once per revolution of the drum 9 at the commencement of the scanning of the raster and as a scanning pulse during scanning either the edge of the raster foil or a special locating mark on the edge of the foil which is drawn more heavily than the raster elements. At the same time as this beam deflection, the scanning pulses occurring at the output of the threshold limiting stage 13 control the brightness of the light spot produced by the cathode beam through the Wehnelt cylinder 20. Motor 29 drives mechanical movement 30.

An enlarged image of the raster is formed on the screen 26 so that cathode ray tube as shown in FIG. 2, may be used as a monitor.

The lines which form the raster pattern extend at a certain small angle to the horizontal due to the continuously varying vertical deflection voltage corresponding to the advance of

the scanners. However, since the speed of advance is very small in comparison to the scanning speed, the tilt of the lines is very negligible.

The method, according to this invention, may be used to advantage in picture telegraphy so as to reproduce a picture sent un rastered as a rastered picture at the receiver and it also can be used when metal cylinders are to be engraved by means of laser beams.

It will be understood that modifications and variations may be effected without departing from the spirit and scope of the novel concepts of the present invention.

We claim as our invention:

1. Means for reproducing a rastered picture from a continuous tone picture comprising:

a first driving means;

three drums driven by said first driving means;

a first scanning head in scanning relation to the first drum and the continuous tone picture mounted thereon and producing an electrical output;

a second scanning head mounted in scanning relationship to the second drum and a raster pattern mounted on said second drum and said second scanning head producing an electrical output;

means for mixing the electrical outputs of said first and second scanning heads for effectively masking the image; a recording head reproducing an image mounted in scanning relationship to the third drum and receiving the output of said mixing means and converting said output to an image;

a recording medium mounted on the third drum; and, a second driving means connected to the first and second scanning heads and the recording head to move them relative to the drums.

2. Means for reproducing a rastered picture according to claim 1 comprising a threshold circuit between said mixing means and the recording head.

3. Means for reproducing a rastered picture according to claim 2 comprising a cathode ray tube monitor connected to said threshold circuit and producing said rastered picture.

4. Means for reproducing a rastered picture according to claim 3 comprising means for horizontally and vertically scanning the beam of said cathode ray tube and synchronizing it with the drums and scanning heads.
